UNITED STATES PATENT OFFICE.

GILBERT W. GOODRIDGE, OF FAIRFIELD, CONNECTICUT, ASSIGNOR TO THE BRYANT ELECTRIC COMPANY, OF BRIDGEPORT, CONNECTICUT, A CORPORATION OF CONNECTICUT.

LAMP SOCKET.

Application filed October 14, 1922. Serial No. 594,551.

To all whom it may concern:

Be it known that I, GILBERT W. GOODRIDGE, a citizen of the United States, residing at Fairfield, in the county of Fairfield and State of Connecticut, have invented certain new and useful Improvements in Lamp Sockets, of which the following is a specification.

My invention relates to sockets, and particularly to an adjustable mounting for candle sockets. The object of my invention is to provide a simple and efficient adjustable standard for carrying the socket, and by which the position of the latter may be varied in accordance with the length of the candlelight casing which forms an element of an electric candle fixture.

In the accompanying drawing—
Fig. 1 is a vertical section through an electric candle fixture in which my invention is embodied in one form;

Fig. 2 is a side elevation of the socket and its supporting standard viewed at right angles to Fig. 1;

Fig. 3 is a broken front elevation of portion of the standard drawn to a larger scale; and

Fig. 4 is a section on the line 4—4, Fig. 3.
In an electric fixture of the candle type, the lead wires are generally carried to the lamp socket through a conduit 5, or the like, provided with a threaded end 6 to which the socket fitting is secured. In the form shown the cup 7 on which the candle-like casing 8 rests is engaged between a lock nut or bushing 9 and the nipple 10 at the lower end of the standard which carries the lamp socket. Casings such as 8 are not of uniform length or style, but vary within fairly wide limits to meet the tastes of different architects and manufacturers. It is advisable therefore to make the socket-supporting standard adjustable to accommodate the position of the socket to the length of the casing 8. Various devices for this purpose have been heretofore suggested, but for the most part have proved not altogether satisfactory in practice by reason of the difficulty of adjustment or the instability of the latter after it is made. The present invention provides an improved adjustable standard of this general type.

While my invention may be embodied in variously differing specific forms, I have illustrated a construction which is practical and efficient. As here shown, the standard comprises upper and lower lengths 11 and 12, preferably in the form of straps struck from sheet metal. The lower section 11 is secured in any suitable way to the nipple 10, as for instance by offsetting therefrom a foot piece 13 pierced to receive the shouldered upper end of the nipple 10, the margin of which is staked over the foot piece to permanently secure the parts together. The upper end of section 12 of the standard is preferably divided and spread to afford a pair of legs 14 and 15, which are secured to the lower face of the socket body 16 by means of screws 17, and are so spaced apart that they straddle the wire passageway 18—the socket shown being of the type indicated in the patent to Burton No. 1,245,673, dated November 6, 1917. Inasmuch as the details of the socket do not enter into the present invention, they are not described.

The adjustment of the upper and lower sections of the standard with respect to each other, is effected by means of a rack and pinion device. To this end the upper section 12 is longitudinally slotted at 19, one side of the slot being notched to form the teeth 20 of a rack. The lower section 11 has journalled therein a stud 21 passing through the slot 19 and carrying on its squared area 22 a pinion 23 meshing with the rack 20. One end of the stud 21 is provided with a head 24 slotted at 25 to receive a screw driver. Its other end is spread at 26 above a strong spring washer 27 which is constantly under relatively heavy stress. Inasmuch as a flat washer 28, straddling the slot 18 and bearing against the face of the section 12 on opposite sides of the slot 19, is located beneath the head 24 of the stud 21, the spring 27 serves to hold the parts assembled with a friction grip sufficient to prevent accidental displacement of the two sections 11 and 12 of the standard by gravity, or under the influence of vibration to which the fitting may be subjected. At the same time, the stress of the washer is not so great that the stud may not be rotated by a screw driver, and the section 12 of the standard thus dis-

placed with respect to the section 11 through the rack and pinion engagement between the parts, and the spacing of the socket from the attaching nipple 10 thus varied. 5 In order to guide the sections with respect to each other, and to hold them in alignment, one or the other of the sections, here section 11, is provided with lateral flanges 29 which embrace the margins of section 12. 10 The construction is simple and effective for its purpose. It will be noted that the spring 27 not only holds the two sections 11 and 12 of the standard in frictional engagement, but also that it exerts a frictional 15 drag on the pinion 23. Inasmuch as the latter has a positive engagement with the rack 20, the friction between the sections is augmented by the frictional drag on the pinion. The sections are thus held very firmly against 25 anintentional relative displacement—but may be readily adjusted by means of a screw driver. It may be pointed out, moreover, that this frictional engagement between the parts is constant, owing to the fact that the spring is under constant stress—and there is no danger of slippage through the loosening of set screws or the like. The standard is readily manufactured from sheet metal parts, with the exception of the stud 21, 30 which may itself be readily shaped from lengths of rod. The details of construction may be varied without departing from the underlying thoughts which will be apparent from the foregoing, and which I claim as my 35 invention.

I claim—

1. An electric lamp socket and a supporting standard therefor, comprising a pair of relatively displaceable members, one of which 40 carries the socket, and the other of which is adapted to be mounted on a support, a rack and pinion connection between said members for relatively displacing the same, and constantly acting friction means for

holding the members in the relative positions 45 to which they are thus adjusted.

2. An electric lamp socket and a supporting standard therefor, comprising a pair of relatively displaceable members, one of which carries the socket, and the other of 50 which is adapted to be mounted on a support, a rack and pinion connection between said members for relatively displacing the same, and spring means for holding the members in the relative positions to which they are 55 thus adjusted.

3. An electric lamp socket and a supporting standard therefor, comprising a pair of relatively displaceable members, one of which carries the socket, and the other of 60 which is adapted to be mounted on a support, a rack and pinion connection between said members for relatively displacing the same, and a spring exerting a constant drag on the pinion to prevent rotation. 65

4. An electric lamp socket and a supporting standard therefor, comprising a pair of relatively displaceable members, one of which carries the socket, and the other of 70 which is adapted to be mounted on a support, a constant positive engagement between said members and yielding means tending to maintain said engagement.

5. An electric lamp socket and a supporting standard therefor, comprising a pair of 75 relatively displaceable members, one of which carries the socket, and the other of which is adapted to be mounted on a support, and spring means tending constantly to maintain said members in adjusted position, together with cooperating gear elements carried by the respective members and constantly intermeshing, one of said gear members being rotatable and subject to the drag of 80 said spring means. 85

In testimony whereof I have signed my name to this specification.

GILBERT W. GOODRIDGE.
